[57] CLAIM

The ornamental design for a personal notebook computer with an integrated trackball, as shown and described.

DESCRIPTION

FIG. 1 is a top front and left side perspective view of a personal notebook computer with an integrated trackball showing my new design with the screen closed; FIG. 2 is a top front and left side perspective view thereof with the screen open;

FIG. 3 is a front elevational view thereof with the screen closed;

FIG. 4 is a rear elevational view thereof;

FIG. 5 is a right side elevational view thereof;

FIG. 6 is a left side elevational view thereof;

FIG. 7 is a bottom plan view thereof;

FIG. 8 is a right side elevational view thereof with the screen open;

FIG. 9 is a left side elevational view thereof;

FIG. 10 is a top front and left side perspective view of a second embodiment thereof with the screen closed; and,

FIG. 11 is a top front and left side perspective view thereof with the screen open.

The undisclosed views of the second embodiment are identical in appearance to those of the first embodiment.
